UNITED STATES PATENT OFFICE.

ALFRED M. DEMUTH, OF CHICAGO, ILLINOIS, ASSIGNEE TO DEMUTH MANUFACTURING COMPANY, OF CHICAGO, ILLINOIS, A CORPORATION OF ILLINOIS.

STEAM TABLE FOR FOOD.

Application filed July 18, 1921. Serial No. 485,562.

To all whom it may concern:

Be it known that I, ALFRED M. DEMUTH, a citizen of the United States, residing at Chicago, in the county of Cook and State of Illinois, have invented certain new and useful Improvements in Steam Tables for Food, of which the following is a specification.

This invention relates to improvements in what is commonly termed steam tables, particularly adapted though not necessarily limited in its use for keeping hot or warm, cooked articles of food and to which articles ready access may be had, the table being so constructed that the steam from the heating medium will not only be prevented from escaping but will also be prevented from coming into contact with the articles of food or the hands of the attendant.

0 A further object is to provide an improved self-contained table of this character having means whereby the liquid which is converted into steam may be automatically supplied and replenished when necessary, thereby obviating the necessity of having to fill or supply the same or having to watch the apparatus, and also rendering it possible to use the table with a very small supply of liquid which does not cover the entire bottom of 30 the vapor chamber, so that the liquid will be quickly converted into steam or vapor, thereby conserving fuel, means being also provided whereby the supply of liquid may be entirely cut off from the table when desired.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention and in which—

45 Figure 1 is a view partly in side elevation, partly broken away and partly in section.

Figure 2 is a top plan view.

Figure 3 is a vertical sectional view as 50 taken on line 3—3, Figure 1.

Figure 4 is a side elevation of the liquid supply tank.

Referring more particularly to the drawings the numeral 10 designates generally a 55 liquid chamber which may be of any desired

size and configuration, the bottom 11 of the chamber being so constructed as to form a trough or channel 12 adjacent the transverse center thereof and which channel extends for the entire length of the chamber. 60 The channel may be formed in any suitable manner but preferably by inclining the bottom 11 downwardly from the sides thereof toward the center, and so as to form a trough or channel for maintaining a supply of liquid in the chamber and which supply does not cover the entire bottom. The top of the chamber may also be formed in any suitable manner but is preferably shaped to form a series of open receptacles 13, which are 65 preferably of a somewhat shallow construction and project into the chamber so that they will be out of contact with the remaining walls of the chamber, and these receptacles 13 are also out of communication with 70 the interior of the chamber. Additional and similar receptacles 14 may also be formed in the top, preferably adjacent one end thereof but these receptacles 14 are preferably somewhat deeper than the receptacles 13 and are adapted to receive and hold suitable food containers 15. The chambers 13 may also receive suitable food containers or 75 trays 16.

The tank thus formed is supported in any suitable manner and at any suitable height and the tank preferably constitutes the top of the compartment 17 that is arranged therebeneath, the whole being supported preferably by means of suitable legs or supports 18. This compartment 17 is provided with an open side 19 adapted to be closed by suitable closures 20 that slide in suitable grooves or guideways 21. Arranged within the compartment 17 are suitable burners 22 85 which are disposed preferably adjacent the lowermost portion of the bottom 11 of the tank for heating the same, and the burners are supplied with fuel through a suitable pipe 23 having connection (not shown) with 90 any suitable source of supply of fuel.

The walls of the compartment 17 are preferably provided with a series of apertures or openings 24 to permit air to enter for the purpose of supporting combustion.

Liquid is supplied to the chamber 10 preferably from a tank or liquid supply holder 25 which may be of any suitable size and configuration and is arranged preferably adjacent one end of the table, being supported 100

thereby by means of a suitable bracket 26 connected with the table and also with the tank. Leading from the tank 25 is a discharge outlet pipe 27 which has communication as at 28 with the chamber 10 preferably at the lowermost point of the bottom, the opening 28 being disposed at a predetermined point above the lowermost point of the bottom or the channel 12, so as to maintain a predetermined supply of liquid in the trough or channel 12, in a manner to be set forth. A suitable valve 29 may be provided in the discharge pipe 27 for controlling the delivery of the liquid to the chamber 10, when desired, and a draw off pipe 30 leads from the bottom of the trough 12 and is controlled by means of a suitable valve 31, thereby rendering it possible to drain the water from the chamber 10 when desired. The tank or supply holder 25 is provided with a fill opening closed by a suitable closure 32 and a gage 33 having a pet cock 34, of the usual construction, may also be provided for the tank 25. In use, and assuming that the chamber 10 is empty, no water being contained in the trough or channel 12, and the valve 31 being closed, the valve 29 is also closed and the cap or closure 32 removed. The tank 25 may then be filled with water after which the closure 32 is placed in position and this will hermetically seal the tank. The valve 29 may then be opened and the water will flow from the tank 25 into the trough 12 of the chamber 10 until the water level in the trough 12 reaches a point sufficient to close the outlet opening 28 of the pipe 27 at which time the supply of water from the tank 25 will be automatically controlled or stopped. As the water in the trough 12 is consumed and the water level lowers, the supply will be automatically replenished and controlled by the change of the water level in the trough 12. When it is desired to entirely shut off the supply of water from the tank 25, the valve 29 is closed.

By the provision of the trough 12 it will be manifest that a comparatively small supply of liquid will be necessary and it will be manifest that the liquid does not cover the entire bottom of the chamber 10. This renders it possible to rapidly heat the liquid to convert the same into steam or vapor with a small amount of fuel, thereby reducing expense and conserving fuel and at the same time producing a rapid conversion of the liquid into steam.

A safety blow off device 35 of any suitable or well known construction may be connected with the chamber 10 to insure safety and this blow off device 35 is set to operate at a predetermined pressure so that when the pressure within the chamber 10 exceeds the point at which the valve 35 is

set, the steam will automatically escape until the pressure is reduced to the proper point. This operation will continue during the operation of the device and it will therefore be manifest that the degree of pressure in the chamber 10 will be controlled by the blow off device 35.

A suitable ledge or support 36 may be provided to extend along one side of the table and is connected thereto by means of suitable brackets 37 and a suitable support 38 may also extend along the opposite side of the table and is supported by means of suitable brackets 39.

With this improved construction, it will be manifest that a self-contained apparatus is provided and it will also be manifest that it will necessitate not only a small supply of liquid in the chamber 10, but the device or the means of supplying and replenishing the liquid in the chamber 10 will be automatically controlled thereby rendering it unnecessary to watch the apparatus and also obviate the necessity of having to refill the chamber when the liquid therein is consumed, as has heretofore been necessary in devices of this character.

It will also be noted that the blow off device 35 is arranged between the end of the tank 25 and the end of the support or ledge 38 as is also the gage 33, so that these parts will be protected and will be out of the way so that they cannot be injured.

While the preferred form of the invention has been herein shown and described it is to be understood that various changes may be made in the details of construction and in the combination and arrangement of the several parts, within the scope of the claims, without departing from the spirit of this invention.

What is claimed as new is:

1. A self-contained steam table of the character described embodying a closed chamber for holding a non-circulating liquid intended to be converted into vapor, said chamber having a portion shaped to form receptacles extending into the chamber and opening through one wall thereof, said receptacles being closed to the interior of the chamber, a closed liquid supply holder, and means whereby the said supply will automatically maintain the liquid at a predetermined level in the said liquid chamber.

2. A self-contained steam table of the character described embodying a closed chamber for holding a non-circulating liquid intended to be converted into vapor, said chamber having a portion shaped to form receptacles extending into the chamber and opening through one wall thereof, said receptacles being closed to the interior of the chamber, a closed liquid supply holder, a connection between the said supply

holder and the chamber whereby the supply will automatically maintain the liquid at a predetermined level in the said liquid chamber, means for controlling at will the delivery of the liquid from the supply holder into the said chamber, and means for heating the chamber to convert the liquid into vapor.

3. A self-contained steam table of the character described embodying a closed chamber for holding a non-circulating liquid intended to be converted into vapor, said chamber having a portion shaped to form receptacles extending into the chamber and opening through one wall thereof, said receptacles being closed to the interior of the chamber, a closed liquid supply holder, a connection between the said supply holder and the chamber whereby the supply will automatically maintain the liquid at a predetermined level in the said liquid chamber, means for controlling at will the delivery of the liquid from the supply holder into the said chamber, means for heating the chamber to convert the liquid into vapor, and a safety blow off device for the said chamber.

4. A self-contained steam table of the character described embodying a closed chamber for holding a non-circulating liquid intended to be converted into vapor, the upper wall of the chamber being shaped to form a plurality of open receptacles projecting into the chamber and spaced from the remaining walls thereof and being closed to the interior of the chamber, the bottom of the chamber inclining downwardly towards the transverse center to form a comparatively shallow trough for the liquid and extending lengthwise of the chamber, a closed liquid supply holder connected with the chamber and discharging thereinto adjacent the bottom thereof, means for controlling at will the delivery of the liquid into the chamber, a safety blow off for the chamber, and a burner arranged beneath the lowermost portion of the bottom of the chamber.

5. A self-contained steam table of the character described embodying a closed chamber for holding a non-circulating liquid intended to be converted into steam, the upper wall of the chamber embodying one or more open receptacles projecting into the chamber and spaced from the remaining walls thereof and being closed to the interior of the chamber, a closed liquid supply tank supported by the table, said tank having a fill opening, a closure for the opening to hermetically seal the tank, a connection between the tank and the chamber whereby the contents of the tank will be delivered into the chamber, a valve in the connection, and a safety blow off for the chamber.

6. A self-contained steam table of the character described embodying a closed chamber for holding a non-circulating

liquid intended to be converted into steam, the upper wall of the chamber embodying one or more open receptacles projecting into the chamber and spaced from the remaining walls thereof and being closed to the interior of the chamber, a closed liquid supply tank supported by the table, said tank having a fill opening, a closure for the opening to hermetically seal the tank, a connection between the tank and the chamber whereby the contents of the tank will be delivered into the chamber, a valve in the connection, and a safety blow off for the chamber, a portion of the bottom of the chamber at the center thereof being lower than the remaining portion of the bottom to form a trough like portion for the liquid, said trough like portion extending lengthwise of the chamber.

7. A self-contained steam table of the character described embodying a closed chamber for holding a non-circulating liquid intended to be converted into steam, the upper wall of the chamber embodying one or more open receptacles projecting into the chamber and spaced from the remaining walls thereof and being closed to the interior of the chamber, a closed liquid supply tank supported by the table, said tank having a fill opening, a closure for the opening to hermetically seal the tank, a connection between the tank and the chamber whereby the contents of the tank will be delivered into the chamber, a valve in the connection, a safety blow off for the chamber, a portion of the bottom of the chamber at the center thereof being lower than the remaining portion of the bottom to form a trough like portion for the liquid, said trough like portion extending lengthwise of the chamber, and a draw off for the liquid in the chamber.

8. A steam table of the character described embodying a closed chamber for holding a non-circulating liquid, open receptacles extending into the chamber through the top thereof and spaced from the remaining walls of the chamber, the bottom of the chamber being shaped to form a liquid channel disposed below the remaining portion of the bottom for maintaining the liquid in the chamber in a clearly defined zone of a width considerably less than the width of the said bottom, means for automatically maintaining the liquid in the chamber at a predetermined level, and means exterior of the chamber for treating the liquid.

9. A steam table of the character described embodying a closed chamber for holding a non-circulating liquid, open receptacles extending into the chamber through the top thereof and spaced from the remaining walls of the chamber, the bottom of the chamber being shaped to form a liquid channel disposed below the remaining portion of the bottom for maintaining the liquid in the

chamber in a clearly defined zone of a width considerably less than the width of the said bottom, a closed liquid supply tank connected with the table, a connection between 5 the tank and chamber, the outlet of the connection being so disposed with relation to the bottom of the said channel as to automatically maintain the liquid at a predetermined level in the channel, and means 10 exterior of the chamber for heating the liquid therein.

10. A steam table of the character described embodying a closed chamber for holding a non-circulating liquid, open receptacles extending into the chamber through the top thereof and spaced from 15 the remaining walls of the chamber, the bot-

tom of the chamber being shaped to form a liquid channel disposed below the remaining portion of the bottom for maintaining the liquid in the chamber in a clearly defined zone of a width considerably less than the width of the said bottom, a closed liquid supply tank connected with the table, a connection between the tank and chamber, means for controlling at will the said connection, means exterior of the chamber for heating the liquid therein, and a safety blow off device for the table.

In testimony whereof I have signed my name to this specification on this 13th day of July, A. D. 1921.

ALFRED M. DEMUTH.
